Primary Examiner — Sheryl Lane*Assistant Examiner* — Samantha N Wood(74) *Attorney, Agent, or Firm* — Grumbles Law PLLC;
Brittany Nanzig(57) **CLAIM**

The ornamental design for a tote bag, as shown and described.

DESCRIPTION

FIG. 1 is a front elevational view of a tote bag showing our new design.

FIG. 2 is a back elevational view of the tote bag.

FIG. 3 is a right side elevational view of the tote bag.

FIG. 4 is a left side elevational view of the tote bag.

FIG. 5 is a bottom plan view of the tote bag.

FIG. 6 is a front perspective view of the tote bag.

FIG. 7 is a back perspective view of the tote bag; and,

FIG. 8 is a bottom perspective view of the tote bag.

The lighter broken lines depict stitching and form part of the claimed design. The bolder broken lines in the drawings depict parts of the tote bag that form no part of the claimed design.

1 Claim, 3 Drawing Sheets(56)
